UNITED STATES PATENT OFFICE

WILBUR R. McCREARY, OF KANSAS CITY, MISSOURI

DESIGN FOR A COMBINATION SMOKER'S SET

Application filed November 7, 1931. Serial No. 41,655. Term of patent 3½ years.

To all whom it may concern:

Be it known that I, WILBUR R. McCREARY, a citizen of the United States, residing at Kansas City, in the county of Jackson and State of Missouri, have invented a new, original, and ornamental Design for a Combination Smoker's Set, of which the following is a specification, reference being had to the accompanying drawings, forming part thereof, in which:

Fig. 1 is a perspective view of a combination smoker set showing my new design.

Fig. 2 is a side elevation of said combination smoker's set.

Fig. 3 is a plan view of the combination smoker's set.

I claim:

The ornamental design for a combination smoker's set as shown.

WILBUR R. McCREARY.
